PENNSYLVANIA

IMPELLING DEVICE FOR COOLING SYSTEMS OF INTERNAL COMBUSTION ENGINES

Application filed November 3, 1931. Serial No. 572,866.

The invention relates to impelling devices for cooling systems of internal combustion engines, and has for its object to provide, in connection with such a system, a rotary pump driven from a moving portion of the engine, and constructed in a manner whereby the use of packing is eliminated.

A further object is to provide a pump in the return pipe leading from the radiator to the engine jacket and driven by a flexible shaft having a driving connection with the moving parts of the engine, said flexible shaft being rotatably mounted in a tubular member having a loop extending above the water level within the radiator to prevent leakage from the pump through the tubular member to an extent where it would leak from the tubular member. Also to provide a ground joint connection between the pump and the tubular member for insuring a tight joint and eliminating the use of packing.

A further object is to rotate the flexible shaft having convolutions in a direction whereby water, which may seep into the tubular member will not be elevated by the convolutions so as to pass over the upper end of the looped tubular member.

A further object is to positively seal the pump casing after assembling of the rotor therein by welding or otherwise securing the cover plate thereon.

A further object is to provide the cover plate with an extension boss in which one end of the rotor shaft is rotatably mounted, and to provide a coupling connection between the tubular member and the boss for forming a close ground connection between the cover of the pump casing and the tubular member.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a perspective view of the device

showing the same applied to a conventional form of internal combustion engine and radiator.

Figure 2 is a side elevation of an internal combustion engine and radiator, showing the device applied thereto.

Figure 3 is a horizontal sectional view through the rotary pump and a portion of the return pipe.

Figure 4 is a vertical transverse sectional view through the pump.

Figure 5 is a longitudinal sectional view through one end of the tube and flexible shaft.

Figure 6 is a side elevation of the adjustable bracket for supporting the driving end of the tubular member and the drive pulley.

Referring to the drawing, the numeral 1 designates a conventional form of internal combustion engine and 2 a radiator into which the cooling fluid passes from the engine through the discharge pipe 3. The water, after passing through the radiator 2, returns to the engine through the return pipe 4 in the usual manner. The return pipe 4 is provided with the usual flexible connection 5, and the pump casing 6 is inserted in the flexible connection 5 with its ends 7 held therein by clamps 8. The pump casing is preferably formed from a single piece of material as clearly shown in Figures 3 and 4 with a removable cover 9, which is welded to the casing at 10 after the bladed rotor 11 is placed within the casing, so as to form a positive closed casing, and one without packing.

Rotor 11 has the lower end 12 of its shaft rotatably mounted in a downwardly extending member 14 formed integral with the casing 6, and on which member is placed a grease cup 15 having a threaded follower 16, so that grease within the cup may be forced, from time to time, into the bearing of the lower end 12 of the shaft, for lubricating the same. Cover 9 is provided with an upwardly extending boss 17.

Shaft 13 is provided with radial blades 18 which may vary in number, and during the operation of the device the shaft rotates in the direction of the arrow *a*, so that the water

passing out of the lower end of the radiator 2 is forced to circulate through the engine 1, pipe 3 and radiator 2.

The upper end of the shaft 13 is rotatably mounted in a boss 17, and connected to the boss 17 by means of a coupling 19 is a pliable tubular member 20, preferably formed from copper. It will be noted that the tubular member 20 has a ground connection 21 with the boss 17, therefore leakage around the thread of the coupling 19 is positively prevented at all times, and the use of packing eliminated. Tubular member 20 extends upwardly and is provided with a loop 22, which is above the upper end of the overflow pipe 23^a, the purpose of which will presently appear. Tubular member 20 is provided with a downwardly extending portion 23, which terminates in a horizontally and inwardly extending arm 24 supported by the sleeve 25 of a supporting bracket 26, which bracket is secured to the engine 1 and is formed from threaded shaft sections 27 having right and left hand thread and connected together by a sleeve 28, which sleeve, when rotated, will adjust the horizontal portion 24 of the tubular member 20 inwardly and outwardly for properly positioning the drive pulley 29 in relation to the flight 30 of the fan belt 31. By providing an adjustable bracket as shown in Figure 6, it is obvious that the device may be adjusted to various types of vehicles, and by making the pipe 20 flexible or pliable, it is obvious it can be bent to form the loop 22 according to various engine structures and locations of parts.

It will be noted that in the pump and pump casing described, the use of packing is entirely eliminated, therefore it will be seen that the many difficulties incident to packed pumps are overcome, and the pump can be easily and quickly inserted in the flexible pipe section 5.

Secured by means of a rectangularly shaped extension 32 to the upper end of the shaft 13 is a flexible shaft 33, which shaft is formed from wire convolutions as clearly shown in Figure 5. The shaft extends upwardly through the pliable tubular member 20 through the loop 22 therein and the horizontal portion 24 and is connected by welding at 34 to the shaft 35 of the drive pulley 29. It will be seen that as the drive pulley 29 is rotated by the flight 30 of the fan belt 31, the flexible shaft 33 will rotate and impart rotation to the pump rotor 11, however it has been found that where spring convolutions are used in the flexible shaft, said shaft should be rotated in a direction whereby water, which may seep through the boss 17, around the shaft 13 into the flexible member 20, will not be lifted by said convolutions, during their rotations, over the loop 22, and if properly positioned as shown in Figure 4, the water will not be lifted.

From the above it will be seen that a pump is provided in connection with a circulating system of an internal combustion engine, which is absolutely free of packing, driven from a moving portion of the engine through a flexible shaft in a tubular pliable member, and which flexible shaft and tubular pliable member allow the device to be applied to various pipes of internal combustion engines without varying the construction thereof. It will also be seen that the pliable tubular member 20 allows adjustment range.

The invention having been set forth what is claimed as new and useful is:—

1. The combination with an internal combustion engine having a circulating cooling system, a radiator in connection with said cooling system in which a liquid level is maintained, pipe connections between said radiator and engine, a pipe in one of said pipe connections, of a flexible drive connection between said pump and a movable part of the engine and a pliable tubular member connected to the pump and supporting the flexible driving connection. 80

2. The combination with an internal combustion engine having a circulating cooling system, a radiator in connection with said cooling system in which a liquid level is maintained, pipe connections between said radiator and engine, a pump in one of said connections, of a flexible driving connection between said pump and the engine, a pliable tubular member through which said flexible driving connection extends, said pliable tubular member extending to a position above the liquid level in the radiator. 95

3. The combination with an internal combustion engine having a circulating cooling system, a radiator in connection with said cooling system in which a liquid level is maintained, a discharge pipe connecting the radiator and the engine, a pump in said discharge connection, of a flexible driving connection between said pump and the engine, a pliable tubular member through which said flexible driving connection extends, said pliable tubular member being looped to a position above the liquid level in the radiator. 105

4. The combination with an internal combustion engine having a circulating cooling system, a radiator in connection with said cooling system, a pipe discharging liquid from the radiator into the engine, a pump in said discharge pipe, of a flexible drive connection between said pump and the engine, a fan belt carried by the engine and driven thereby, a pulley carried by the flexible drive connection, a pliable tubular member in which said flexible drive connection is rotatably mounted, said pliable tubular member being looped to a position above the water level in the radiator. 115

5. The combination with an internal combustion engine having a circulating cooling

system, a radiator in connection with said cooling system, a discharge pipe connection between the radiator and the engine, a pump in said discharge pipe, of a coiled flexible drive connection between said pump and the engine, a pliable tubular member through which said flexible driving connection extends, said pliable tubular member extending to a position above the liquid level in the 5 radiator, said pliable driving connection being formed from a plurality of convolutions, said pliable driving connection being rotated in a direction whereby the convolutions thereof will not lift liquid through the 10 15 tubular member.

6. A device as set forth in claim 4 including means whereby the pulley can be adjusted towards and away from the fan belt.

In testimony whereof they hereunto affix 20 their signatures.

GEORGE S. MOORE.
